SURGICAL FRACTURE REDUCING
APPLIANCEEarl E. Longfellow, Warsaw, Ind., assignor to
Harry Herschel Leiter, Warsaw, Ind.

Application January 15, 1934, Serial No. 706,656

1 Claim. (Cl. 128—84)

This invention relates to a surgical fracture reducing appliance, more particularly to apparatus for reducing a fractured forearm and subsequently holding it in a definite position during application of a plaster cast, or for other treatment.

The primary object of the invention is to provide means whereby traction is applied to the bones of the forearm or selectively to the humerus.

The invention further aims to provide a device of this type in which the parts may be easily and quickly manipulated not only to selected positions but also for applying traction to bones of an injured member.

In the drawing:

Fig. 1 is a side elevation of the invention partly broken away and in section;

Fig. 2 is a top plan view; and

Fig. 3 is an enlarged section taken on line 3—3 of Fig. 2.

In proceeding in accordance with the present invention a base 1 is provided which has caster wheels 2 and anchor clips 3. A post 4 extends upwardly from the base 1 and has a telescopic upper section 5 which latter is secured in adjusted position by means of a thumb screw 6. A stem 7 is rotatably and removably received in the upper end of the section 5 and is adjustably held therein by means of a thumb screw 8, the stem carrying a bracket 7' that has a rock shaft 9 adjustably mounted therein. The inner end of the rock shaft is provided with a tubular member 11 in which is received the stem or shank 12 of an arcuate padded arm rest 13, the latter being provided with an anchor strap 14 to hold the rest in the arm pit of the patient. The outer end of the rock shaft 9 has pivoted thereon two swinging arms 15 and 16' which are adjustably secured by means of a bolt 17. The arm 15 has an adjustable extension 16 held in adjusted position by means of a thumb screw 17, and the arm 16' has an extension 16'' held in adjusted positions therein by a thumb screw 17'.

The outer end of the extension 16 has an upturned member 18 that has adjustably secured therein by means of a thumb screw 19 a post 20 in the upper end of which is positioned a threaded rod 21 which latter is manually rotated by means of a hand-operated member 22.

A hand rest 23 is connected to a rod 24 which latter is telescopically adjustable in a tube 25 that is pivoted at 26 to the upturned member 18 on the extension 16. A thumb screw 25' holds the parts 24 and 25 in their extended or contracted positions.

A yoke 27 is connected to the threaded rod 21 by means of a swivel and ring 28 and complementary hook 29. The outer arms of the yoke removably support a skeletal pin 30 that extends through perforations made in the bones of the forearm.

The extension 16'' has an upright 31 which latter is provided with a telescopic post 32 that is secured in adjusted positions therein by means of a set screw 33. The top of the post 32 has a head 34 in which is disposed a threaded rod 35 having a handle 36' by means of which the rod is adjustably turned. A yoke 36 is attached by means of a swivel and ring 37 and complementary hook 38 to the threaded rod 35 and has removably secured in its outer ends a skeletal pin 39 that extends through perforations made in the bones of the forearm adjacent the ends thereof opposite the location of the pin or needle 30.

In use, the stem 7 is inserted and secured in the stand and the patient is positioned as shown in Fig. 1 so that the rest 13 is disposed under the arm pit of the injured member where it is held by the strap 14 which is applied over the shoulder. The arm is bent at the elbow so that the hand of the patient rests upon the member 23. The forearm bones are then pierced and the needles 30 and 39 are inserted therethrough and secured in the respective yokes 27 and 36. By adjusting the extensions 16 and 16'' in the arms 15 and 16' respectively the yokes are spaced to suit the length of the patient's forearm and by manipulating the threaded rods 21 and 35 the desired tension is thereby applied through the medium of the needles to the forearm bones. More or less traction is also applied to the femur bone by positioning the arm 15 at an angle as shown in dotted outline in Fig. 2 and manipulating the threaded rod 35.

The apparatus with the injured arm secured therein may be tilted and held stationary by adjustably turning the rock shaft 9 upon its axis and securing same in its supporting bracket 7' by means of the screw 42, which latter extends through the free ends of the sections 40 of the bracket which sections are pivoted together at 41. The bracket 7' has sliding movement on a sleeve 9' which latter is adjustably connected to the rock shaft 9 by means of a thumb screw 43. When the apparatus is thus secured to the body of the patient and the parts are in adjusted positions, the appliance may be disconnected from the stand by removing the stem 7 from the post 4 while the arm of the patient is held in fixed relation to the torso. A plaster cast is applied in the usual

manner after which when desired the appliance is removed from the arm.

It will be apparent that the invention thus embodies two independently swinging frames, composed of the members 15, 16, 18 and 20, and 16', 16'', 31 and 32, each frame carrying a supported needle with means to independently apply traction movement thereto, and that the frames, while held fixed in adjusted relation with each other, are bodily tiltable upon the axis of the rock shaft 9.

I claim:

In a fracture apparatus, a stand, a rock shaft

carried by the stand, means to adjustably hold the rock shaft, a pair of frames pivoted to the rock shaft for independent swinging movement, means to hold the frames in adjusted positions, a member for each frame having a removable needle, means connected to the members and to the respective frames for applying traction to the needles, and means connected to the rock shaft and including a rest to engage the arm pit of the patient for connecting the rock shaft to the shoulder of the patient.

EARL E. LONGFELLOW.
